(57) **CLAIM**

The ornamental design for a spray bottle, as shown and described.

DESCRIPTION

FIG. 1 is a left front perspective view showing my new design; FIG. 2 is a left side elevation view thereof; FIG. 3 is a front elevation view thereof; and, FIG. 4 is a perspective view similar to FIG. 1 but showing the upper portion in a rotated position.

The unshaded area of the face of the spray bottle surrounding the nozzle and extending to the outline of the face forms no part of the claimed design.
